EXTENSION TABLE

Joseph Petrone, Brooklyn, N. Y.

Application August 28, 1951, Serial No. 16,460

Term of patent 14 years

(Cl. D33—14)

To all whom it may concern:

Be it known that I, Joseph Petrone, a citizen of the United States, residing in the Borough of Brooklyn, county of Kings, and State of New York, have invented a new, original, and ornamental Design for Extension Table, of which the following is a specification, reference being had to the accompanying drawing, forming part thereof.

Figure 1 is a perspective view of an extension table embodying my new design;

Figure 2 is a perspective view of the table of Fig. 1 in extended position.

The opposite side and end are similar to those shown.

I claim:

The ornamental design for an extension table, as shown and described.

JOSEPH PETRONE.
